ANTHONY S. BUSK, OF POUGHKEEPSIE, NEW YORK, ASSIGNOR TO HOE CORPORATION,
OF POUGHKEEPSIE, NEW YORK, A CORPORATION OF NEW YORK

PRINTING MACHINE

Application filed July 10, 1926. Serial No. 121,523.

My present invention relates to printing press cylinders, and particularly to such cylinders when substantially the entire circumference of the cylinder is used either for 5 impression or plate supporting purposes, such as is commonly used in web printing presses.

In cylinders of this type, it is desirable that as much of the surface of the cylinder be 10 utilized for impression purposes as possible and, at the same time, the cylinder should be arranged so that the covering for the cylinder, such as the usual tympan or printing plate, can be securely held to the cylinder and arranged so that its edges will be conveniently 15 accessible, and particularly in the case of a printing plate, so that the plate can be adjusted on the cylinder to bring it in proper printing relation with other plates and other 20 cylinders of the same press. It is the object of my present invention to provide an arrangement by which these ends may be accomplished.

My invention will be best understood from 25 the following description and the annexed drawings of an illustrative embodiment, in which Fig. 1 is a longitudinal elevation of a form cylinder to which my invention has been applied, with a portion of the cylinder 30 removed to better illustrate the construction; Fig. 2 is an enlarged section on the line 2—2 of Fig. 1; Fig. 3 is an enlarged view of a portion of the cylinder shown in Figs. 1 and 2 looking from above in Figs. 1 and 2 and 35 with portions broken away; Fig. 4 is a side elevation, partly in section, of a blanket or impression cylinder embodying one form of my invention, and Fig. 5 is an end view of the cylinder shown in Fig. 4.

40 Like reference characters indicate like parts in the several views.

In the arrangement shown in Figs. 1, 2 and 3, the cylinder is provided with the usual shaft 10 and is itself made up of two semi-cylindrical shells, one of which has a sheet- 45 supporting portion 11 and the other a sheet-supporting portion 12, each of such portions being somewhat less than 180° in circumferential arc. The shell having the portion 11 50 is provided with hubs 13, of which there may

be any desired number spaced along the shaft 10, these hubs being keyed to the shaft by the keys 14. The shell having the supporting portion 12 is provided with hubs 15 which are free to turn on the shaft 10.

At either end of the cylinder is the usual bearer 16, also keyed to the shaft 10 by the keys 17. By this arrangement, it will be noted that the bearers 16 and the shell having the portion 11 are in fixed relation because of their fixed connection to the shaft 10 and that the shell having the portion 12 may be moved around the axis of the cylinder in relation to the bearers and the portion 11.

In order to hold the shell having the portion 12 in desired relation to the remainder of the cylinder, I provide in the illustrative embodiment, a lug 18 on each of the bearers 16, in which lugs are threaded screws 19 having their lower ends bearing against a lug 20 connected to the hub 15 of the shell having the portion 12. Between a portion of the shell 11 and the lug 20 is a compression spring 21 which acts against the pressure of the screws 19.

With the arrangement just described, it will be obvious that when the screws 19 are turned, they will be moved against the lug 20 and this, in turn, will move the shell having the portion 12 clockwise in Fig. 2. On the other hand, if the screws 19 are turned in the opposite direction, then the spring 21 will move the shell having the portion 12 counterclockwise.

In the form illustrated in Figs. 1, 2 and 3, the cylinder is designed as a plate cylinder for a planographic printing press in which the plate P extends entirely around the cylinder with its edges held in suitable clamps located respectively at the adjacent ends of the portions 11 and 12. These clamps are substantially alike and a description of one of them will, therefore, be sufficient.

The end of the portion 11 is provided with a recess having a vertical wall 22 and a bottom 23 and in this recess is placed a removable portion 24 with its side and bottom against the side and bottom of the recess in the portion 11, the outer surface of the por-

tion 24 being turned and ground as a continuation of the surface of the portion 11. The lower part of the portion 24 is provided with an angular projection 25 against which bears 5 a correspondingly angular portion of a plate 26 held to the shell by bolts 27 but arranged in such a way that, while the cooperating angular portions will prevent the portion 24 from moving out radially from the cylinder, it will 10 not prevent motion of the portion 24 longitudinally of the axis of the shaft 10. The plate 26 may be formed continuously across the cylinder or made up of a number of short-length plates.

15 In the portion 24 is a groove having a rectangular portion and also an angular portion at the upper side, and fitting in this groove is a body member 28 forming a part 20 of the plate clamping device, the other portion of the clamping device being formed by a thin plate 29 through which extend screws 30 threaded into the body member 28 and preferably provided with a spring 31 to move the plate 29 outward when the screws 30 are 25 turned to move their heads away from the body member 28. The edge of the plate P is bent and entered between the body member 28 and the plate 29 and is held by the pressure derived from the screwing up of the screws 30. The body member 28 is provided with an 30 upwardly projecting angular portion 32 entering the corresponding angular portion of the groove in the removable portion 24, this angular portion being provided so that the 35 plate will be held closely adjacent the surface of the cylinder.

The body member 28 is also provided at 40 spaced intervals with a number of screw plugs 33 bearing against the rear wall of the groove in the removable portion 24 and means are provided for rotating these screw plugs, which, in the form illustrated, is a hexagonal member 34 entering a hexagonal central opening in the plug 33, the member 34 having a 45 hexagonal bolt head 35 outside of the plate 29 and a circular portion 36 extending through an opening in the plate 29 and provided with a collar 37 pinned to the member 34. When the bolt head 35 is turned, its rotation is communicated through the hexagonal member 34 to the plug 33 and by the rotation of the plug 33 and its pressure against the rear wall of the groove, the body member 28 will be moved 50 outwardly to draw the plate P over the surface of the supporting portion of the shell with which the particular plate clamp being moved cooperates.

In each of the bearers 16 is a large-headed screw 38 having its head bearing against both 55 of the removable portions 24, so that, by turning the screws 38, these removable portions may be moved bodily longitudinally of the cylinder.

It will be understood that the ends of the 60 shell provided with the plate clamps have

thickened portions in which the grooves for the removable portions 24 are located and, in order to counterbalance the metal at these ends of the shell, the opposite ends of the portions 11 and 12 are provided with similar projections, as shown best in Fig. 2.

It will also be understood that, because of the closeness with which the ends of the portions 11 and 12 having the plate clamps may approach each other, openings may be provided in each of the plates 29 opposite the respective bolt heads, so that these bolt heads may sink into appropriate recesses in the opposite plate 29. As shown best in Fig. 3, the several bolts 30 and the several plugs 33 in 75 the respective plate clamps are arranged in staggered relation across the cylinder, so as not to interfere with each other.

With the arrangement described, the screws 19 are first manipulated so as to move the portion 12 counterclockwise in Fig. 2 to close up the gap at the bottom and to make the gap at the top as wide as possible. Then plates 29 are opened by unscrewing bolts 30 and the edges of the printing plate P are inserted and the bolts 30 tightened to grip the edges of the plates in the respective plate clamps. Then the screws 19 are manipulated to move the portion 12 clockwise to draw the plate tightly 85 around the cylinder. It will be understood that the design on the printing plate will be positioned on the plate in proper relation to the bend in the printing plate P and also in relation to the gaps between the portions 11 and 12, so that the margins between the design on the portion 11 and the design on the portion 12 will come opposite the gaps between those supporting portions.

If it is found that the plate P needs to be shifted around the cylinder to bring it in proper relation to the other cylinders in a web printing press, for instance, then the members 35 are turned to rotate the plugs 33, one set of plugs being turned to move its body portion 28 outward and the opposite body portion inward and this obviously will shift the plate slightly around the cylinder. Similarly, if after the plate is on the cylinder, it is found necessary to shift it across the cylinder, then this may be done by means of the screws 38 which will move the removable portions 24 to the desired extent and the plate clamps and plate with them.

In the event that the design is not correctly located with respect to the bent edges of the plate P, so that one side of the plate should be shifted without shifting the other, then one set of plugs 33 at one side of the cylinder can be manipulated to move that side of the plate only. For instance, the plugs 33 at the right-hand end of the cylinder in Fig. 1 will be turned so that that end of one of the members 28 will be free to move further into its groove and the plugs 33 at the same end of the other member 28 will be turned so that 115 120 125 130

that end of that member 28 will be moved out of its groove and, by thus throwing the members 28 out of alignment with the axis of the cylinder, one side only of the plate P will be moved.

It will be understood that any of the motions given to the plate P by moving the members 28 into or out of their respective grooves, though small, will be sufficient to take care of any of the usual inaccuracies in locating the design on the plate P and in locating the bends in the plate in proper relation to the design.

By providing the plates 26 with their bolts 27 which are accessible between the heads 35 and the heads of the bolts 30, each of the removable portions 24 may be removed from the cylinder in case any repair is necessary to the plugs 33 or the bolts 30, and this may be done without removing the cylinder from the press or dismounting the cylinder in any way. It will be obvious that in such case, the bolts 27 need be loosened only enough to permit the plate 26 to move outward away from the angular portion 25 of the removable part 24.

It will also be obvious that with the arrangement described, very much narrower margins may be provided than would otherwise be possible. As illustrated, the margins 30 are so small that it would not be possible to insert the edges of the plate in the plate clamps if the two portions 11 and 12 could not be moved relatively to each other. Moreover, by tightening the plate on the cylinder 35 by moving the two shells relatively, it is unnecessary to provide any great circumferential movement for the clamps themselves relatively to the cylinder.

In the arrangement shown in Fig. 4, I have shown my invention applied to an impression or blanket cylinder, the cylinder having a shaft 40 with the relatively fixed shell 41 and the relatively movable shell 42 and with devices similar to those described 45 for the plate cylinder, whereby these shells may be moved relatively to each other. Instead of the plate clamps, the cylinder is provided with a pair of blanket rods 43 to which the blanket B may be attached, as by the plate 50 44 and the screws 45, the ends of the blanket rods being provided with the usual pawl and ratchet arrangement commonly used for such blanket rods. The bearer 46 has openings opposite the ends of these blanket rods, so that such ends may project through the bearer to be provided with the usual squares 47 by which the rods may be turned.

In a manner similar to that previously described for the cylinder shown in Fig. 2, the 55 two shells are moved so as to provide a wide gap at the top of Fig. 5 through which the ends of the blanket B may be inserted and fastened to the rods by the plates and screws 44 and 45. Then the shells are moved relatively to produce a substantially equal gap at

the top and bottom of Fig. 5 and the blanket may be further tightened by turning the rods 43 in the usual manner.

It will be understood that many of the features of my invention may be used independently of the other features and that the arrangement which I have shown is merely illustrative and that the embodiment of my invention may be widely varied.

I claim:

1. A printing press cylinder comprising a pair of semi-cylindrical shells, each having a supporting surface with the sum of the arcs of the two surfaces less than 360° , and means to move said shells relatively around the axis 75 80 of the cylinder.

2. A printing press cylinder comprising a pair of semi-cylindrical shells, each having a supporting surface with the sum of the arcs of the two surfaces less than 360° , sheet- 85 holding means on each shell and each arranged to hold an end of a sheet extending around the cylinder, and means to move said shells relatively around the axis of the cylinder, whereby the sheet held in said sheet- 90 holding means may be stretched.

3. A printing press cylinder comprising a shaft, a pair of semi-cylindrical shells each having a supporting surface forming part of the surface of the cylinder and each of said shells having hubs through which said shaft extends, with the hubs of one shell attached to the shaft and the hubs of the other shell free to turn thereon, and means to move the free shell around the shaft relatively to the fixed 95 100 shell.

4. A printing press cylinder comprising a shaft, a pair of semi-cylindrical shells each having a supporting surface forming part of the surface of the cylinder and each of said shells having hubs through which said shaft extends, with the hubs of one shell attached to the shaft and the hubs of the other shell free to turn thereon, and means to move the free shell around the shaft relatively to the fixed 105 110 shell, said means comprising screws at opposite ends of one of said shells abutting against a portion of the other shell.

5. A printing press cylinder comprising a shaft, a pair of semi-cylindrical shells each having a supporting surface forming part of the surface of the cylinder and each of said shells having hubs through which said shaft extends, with the hubs of one shell attached to the shaft and the hubs of the other shell free to turn thereon, and means to move the free shell around the shaft relatively to the fixed shell, said means comprising springs arranged to bias said supporting surfaces into position with adjacent ends in contact and screws to move said supporting surfaces against the bias of the springs.

6. A printing press cylinder comprising a pair of semi-cylindrical shells, each having a supporting surface of substantially the same 125 130

- length of arc, and each less than but nearly equal to 180° , sheet-holding means on each shell and at adjacent ends of said supporting surfaces, and means to move said shells relatively around the axis of the cylinder and hold the shells in adjusted position.
7. A printing press cylinder having a sheet supporting segment with a groove at the front edge of the segment and beneath the sheet supporting surface of said segment, a body member extending across the cylinder in said groove, means to grip the edge of a sheet to said body member, and body member moving means constructed and arranged to permit substantially circumferential movement of said body member out of alignment with the axis of the cylinder.
8. A printing press cylinder having a sheet supporting segment with a groove at the front edge of the segment and beneath the sheet supporting surface of said segment, a body member in said groove, means to grip the edge of a sheet to said body member, and means to move said body member in said groove longitudinally of the cylinder axis.
9. A printing press cylinder having a sheet supporting segment with a groove at the front edge of the segment and beneath the sheet supporting surface of said segment, a body member in said groove, means to grip the edge of a sheet to said body member, means to move said body member in said groove substantially circumferentially of the cylinder, and means to move said body member longitudinally of the cylinder axis.
10. A printing press cylinder having a sheet supporting segment comprising a relatively long fixed portion and a relatively short removable portion, sheet-holding means on said removable portion, and means to hold said removable portion in position in the cylinder, said last-named means including a member attached to the fixed portion and extending over a projection on said removable portion.
11. A printing press cylinder having a sheet supporting segment comprising a relatively long fixed portion and a relatively short removable portion, said removable portion being positioned in a recess formed at one end of said fixed portion, sheet-holding means on said removable portion, and means to hold said removable portion in said recess.
12. A printing press cylinder having a sheet supporting segment comprising a relatively long fixed portion and a relatively short removable portion, said removable portion being positioned in a recess formed at one end of said fixed portion, sheet-holding means on said removable portion, and means to hold said removable portion in said recess, said last-named means including a plate attached to said fixed portion beneath said removable portion and extending over a projection on said removable portion.
13. A printing press cylinder having a sheet supporting segment comprising a relatively long fixed portion and a relatively short removable portion, said removable portion being positioned in a recess formed at one end of said fixed portion, sheet-holding means on said removable portion, and means to hold said removable portion in said recess, said last-named means including a plate attached to said fixed portion beneath said removable portion and extending over a projection on said removable portion, said removable portion and its recess and said means to hold said removable portion in said recess being constructed and arranged to permit said removable portion to be moved longitudinally of the axis of the cylinder while the removable portion is held against radial movement.
14. A printing press cylinder having a sheet supporting segment comprising a relatively long fixed portion and a relatively short removable portion, said removable portion being positioned in a recess formed at one end of said fixed portion, sheet-holding means on said removable portion, means to hold said removable portion in said recess, said last-named means including a plate attached to said fixed portion beneath said removable portion and extending over a projection on said removable portion, said removable portion and its recess and said means to hold said removable portion in said recess being constructed and arranged to permit said removable portion to be moved longitudinally of the axis of the cylinder while the removable portion is held against radial movement.
15. A printing press cylinder having a sheet supporting segment comprising a relatively long fixed portion with a rectangular recess at one end and a relatively short removable portion in said recess with one side and the bottom of said removable portion fitted to the side and bottom respectively of said recess, sheet-holding means on said removable portion and a holding plate removably connected to the front of said fixed portion and beneath said recess and extending over a portion of said removable portion to hold it in said recess.
16. A printing press cylinder having a sheet supporting segment comprising a relatively long fixed portion with a rectangular recess at one end and a relatively short removable portion in said recess with one side and the bottom of said removable portion fitted to the side and bottom respectively of said recess, sheet-holding means on said removable portion and a holding plate removably connected to the front of said fixed portion and beneath said recess and extending over a portion of said removable portion to hold it in said recess.

- over a portion of said removable portion to hold it in said recess, and means to move said removable portion longitudinally of the axis of the cylinder while said holding plate retains said removable member in said recess.
- 5 17. A printing press cylinder having a sheet supporting segment comprising a relatively long fixed portion with a rectangular recess at one end and a relatively short removable portion in said recess with one side and the bottom of said removable portion fitted to the side and bottom respectively of said recess, sheet-holding means on said removable portion and a holding plate removably connected to the front of said fixed portion and beneath said recess and extending over a portion of said removable portion to hold it in said recess, said sheet-holding means comprising a body member positioned in a groove in said removable portion and beneath the cylindrical surface thereof, and means to clamp the edge of a sheet against said body member.
- 10 18. A printing press cylinder having sheet supporting segments with facing grooves at the front edges of the segments and beneath the sheet supporting surfaces thereof, a body member in each groove, independent means to grip the edge of a sheet to each of said body members, and means to move one of said body members in its groove substantially circumferentially of the cylinder.
